INVENTOR

FRANK M. BELL.
By Thomas L. Ryan
ATTORNEY.

UNITED STATES PATENT OFFICE.

FRANK M. BELL, OF MUNCIE, INDIANA, ASSIGNOR TO ROBERT G. THOMPSON AND
EUGENE B. SIMMONDS, BOTH OF MUNCIE, INDIANA.

TRUCK.

Application filed August 4, 1924. Serial No. 729,899.

This invention relates to improvements in trucks.

The object of my present invention is to provide a truck which is capable of being manufactured at low cost, and which is capable of being easily handled and rendered available for the dependable and safe loading, transportation, and unloading of the heavier kinds of merchandise, such as newsprint paper, roofing and packing paper, barrels of cement, and divers heavy products.

Further purposes of the invention are to provide a truck of the kind described which is rugged and durable and which while being of simple and economical construction has strength to withstand heavy strains, and is capable of such use that a person of ordinary strength and skill, may safely, efficiently, and expeditiously handle and transport all classes of heavy merchandise.

My invention comprises the several features of utility and improved construction, and is embodied in the new combination and arrangement of parts described in the following specification and illustrated in the accompanying drawings. The invention is defined in the appended claims.

The several parts of the invention are identified by suitable characters of reference applied thereto in the different views, in which

Figure 1 is a top plan view of my improved truck.

Figure 2 is a side elevation and sectional view taken on the line 2—2 in Figure 1.

Figure 3 is an end elevation view.

Figure 4 is a vertical transverse sectional view taken on the line 4—4 in Figure 1.

My invention consists of a frame comprising longitudinal parallel members with lateral arms, having downwardly turned ends, a pair of rollers central of the frame, and a pair of rollers at each end of the frame, the last named rollers being of diameter less than that of the central rollers; all of the different parts above referred to, being combined and arranged and having the functions as hereinafter described.

It is practicable to embody my invention in trucks of different sizes and to make minor variations in form, according to special requirements that might be present on

account of peculiarities in the shape of the merchandise packages to be handled.

In the embodiment shown herein and which is intended for general purposes where heavy duty is required, the frame consists of a pair of longitudinal members A and A, made of cast iron, and of the form in cross section, as shown in Figure 4.

Each of these side members has the continuous inclined face B. The ends of these side members have the downwardly turned and inclined faces C and the curved edges D.

Extending laterally from the outer side of each of the said side members and spaced apart as shown in Figure 1, are lateral arms E. Each of these lateral arms is curved downwardly and has the face F. These lateral extensions may be of any desired length and form and may be provided in the integral form as shown, or in the form adapted to be secured or attached to the side members.

In connection with the central and with the end portions of the side members are shafts preferably of cold rolled steel, the central shaft being designated G and the end shafts being designated as H and K.

No machine work is required upon the frame constructed as above described, except the sawing off of the ends of the shafts to proper length and drilling holes therethrough for the cotter pins T.

The central rollers M are of diameter slightly greater than the diameter of the end rollers O and P.

Each roller has a central bore of diameter sufficiently larger than its shaft, to receive the anti-friction pin bearings Q which are disposed between the said bore and the shaft.

On the inner side of each roller and adapted to rest against the outer side of the frame member A is a washer R. On the outer side of each roller is a washer or disk plate S. The location of the transverse hole in each end of the said shafts is such that when the cotter pins T are in place, the rollers are suitably retained on their shafts.

By the novel combination and arrangement of parts just described, there is provided a device upon which there is a minimum of machine work, and which device, while not liable to any injury whatever in its receiving and sustaining of very heavy

loads, is capable of being moved in any direction with the utmost ease. The carrier portion of the frame being close to the surface or floor upon which the truck is being operated, a slight exertion only is necessary to deposit on the truck the heaviest of loads. In propelling the load, it may be tilted so as to rest on four rollers or solely on the central rollers as may be desired.

10 My improved truck is especially intended for use in the moving of paper rolls, and packages, barrels, or hogsheads. In the transporting of paper stock rolls for deposit in low position under the paper making machine, my invention is of economical advantage.

15 To load my improved truck, it is placed with the faces F of the arms E at engagement with the side of the roll; the roll then being simply rolled over the faces F, whence it settles on the frame and is safely retained on the faces B and B.

20 The faces C and edges D of the frame members being rounded, and the tops of the arms E being on a plane above the tops of the rollers M, there is avoidance of any injury to the surface of the packages or merchandise that is being handled.

25 A truck constructed in accordance with my invention is available for the economical handling of the heaviest loads, is not liable to derangement, and needs no attention, except occasionally the use of lubricant at the rollers.

30 **35 Claims:**

1. A truck of the kind described comprising outer parallel shafts, a shaft disposed centrally of and parallel to the outer shafts, side members disposed at a right angle to 35 and engaging the shafts at locations near their ends, lateral arms on the side members provided with downturned ends, retainer devices on the ends of the shafts, and rollers journaled on the ends of the shafts 40 between the side members and the retainer devices.

2. A truck of the kind described comprising side members, outwardly disposed lateral arms having downturned ends, a central 45 transverse shaft to retain the side members spaced apart and having journals thereon, outer transverse shafts to retain the end portions of the side members spaced apart and having journals thereon, rollers retained on the journals of the central transverse shaft and rollers retained on the journals of the outer transverse shafts, the rollers of the central shaft being of diameter greater than the diameter of the rollers of the outer 50 shafts.

3. A truck of the kind described comprising longitudinal frame side members, lateral arms on said side members having downwardly disposed ends, a transverse shaft 55 central of the side members and having pro-

truding end portions, transverse shafts near the ends of the side members, and having protruding end portions, rollers retained and journaled on the end portions of each transverse shaft, the rollers on the central shaft being of diameter greater than the diameter of the rollers on the outer shafts. 70

4. A frame having parallel side members whose top surfaces incline downwardly and toward each other and whose ends are curved 75 downwardly, there being arms that extend laterally from the frame and thence downwardly, a traction roller disposed centrally of each side member, and a roller disposed near each end of the side members, the end 80 rollers being of diameter less than the diameter of the central rollers.

5. A truck consisting of a frame having a centrally depressed portion and centrally disposed rollers, the ends of the frame being curved downwardly, arms extended laterally from the sides of the frames and being curved downwardly at their outer ends, a roller at each end of the frame, of diameter less than the diameter of the central rollers. 85 90

6. A truck, comprising outer parallel metal shafts, a metal shaft disposed centrally of and parallel to the outer shafts, side members disposed at a right angle to 95 and engaging the shafts at locations near their ends, the ends of said side members being turned downwardly, lateral extensions on the side members provided with downturned outer portions, retainer devices on the ends of the shafts, and rollers journaled on the ends of the shafts between the side members and the retainer devices. 100

7. A truck of the character described comprising side frames having inwardly and downwardly inclined faces, outwardly and downwardly inclined lateral arms, transverse end shafts, a transverse shaft intermediate said end shaft, rollers journaled on said shafts, the end rollers being of less diameter than the intermediate rollers, substantially as and for the purposes described. 105 110

8. A truck of the character described comprising two parallel side frames having inwardly and downwardly inclined faces throughout their length, outwardly and downwardly inclined lateral arms, transverse end shafts, a transverse shaft intermediate said end shafts, rollers journaled on said shafts, the end rollers being of less diameter than the intermediate rollers, substantially as and for the purposes described. 115 120

9. A truck of the character described comprising two, parallel side frames having downwardly inclined ends, inwardly and downwardly inclined faces throughout their length and outwardly and downwardly inclined lateral arms, transverse end shafts, a transverse shaft intermediate said end shafts, rollers journaled on said shafts, the end rollers being of less diameter than the 125 130

intermediate rollers, substantially as and for the purpose described.

10. A truck of the character described comprising two parallel side frames having 5 downwardly inclined ends, transverse end shafts, a transverse shaft intermediate said end shafts, rollers journaled on said shafts, the end rollers being of less diameter than the intermediate rollers, the inclined ends 10 of the side frames extending beyond the periphery of the rollers, substantially as and for the purposes described.

11. A truck of the character described comprising parallel side frames having inwardly and downwardly inclined faces 15 throughout their length, outwardly and downwardly inclined lateral arms, transverse end shafts, a transverse shaft intermediate said end shafts, rollers journaled 20 on said shafts, the end rollers being of less diameter than the intermediate rollers, said

lateral arms arranged above and beyond the rollers, substantially as and for the purposes described.

12. A truck comprising longitudinal side 25 frames, spacing shafts and rollers, substantially as described, each of said side frames having laterally downwardly and outwardly inclined arms terminating near the floor, the top surface of said arms being 30 above the periphery of the rollers, substantially as and for the purposes described.

13. A truck of the character described comprising two parallel side frames and spacing shafts and rollers substantially as 35 described, each of said side frames having downwardly inclined ends, inwardly and downwardly inclined faces, and outwardly and downwardly inclined lateral arms 40 terminating near the floor, substantially as described.
